CONTROL CIRCUIT

Oscar A. Pearson, Oak Park, Ill., assignor to Jefferson Electric Company, Bellwood, Ill., a corporation of Illinois

Application April 30, 1941, Serial No. 391,168

3 Claims. (Cl. 176—124)

This invention relates to control circuits, and more particularly to circuits providing safety from shocks and short circuits.

There are circuits in common use which subject inexperienced people to danger of shocks and the electrical apparatus used to damage from short circuits. The adaptation of the particular circuits disclosed herein is to lighting with gas discharge tubes requiring relatively high operating potentials.

It is an object of this invention to provide an electrical control circuit which is automatically de-energized upon the occurrence of an abnormal condition and which requires deliberate resetting, for re-energization.

Another object of this invention is to provide an electrical control circuit which becomes automatically de-energized upon the occurrence of an open circuit and remains normally de-energized during the existence of the open circuit and until deliberately re-energized.

Another object of this invention is to provide a lighting control circuit including a lighting unit, a transformer through which operating potential is applied to the lighting unit, and means for opening the primary circuit of the transformer if and when the secondary winding circuit is opened.

Another object of this invention is to provide a control circuit including a transformer and an electromagnetic switch having a holding coil connected in the circuit of the transformer secondary winding for holding the switch closed and a circuit closing element connected in series with the transformer primary winding.

Another object of this invention is to provide a control circuit including a transformer, an electromagnetically actuated switch having a holding coil connected in the secondary winding circuit of the transformer for holding the switch closed and automatic means for preventing the reclosing of the primary circuit of the transformer for a predetermined length of time after it has been opened.

Further objects and advantages of the present invention will be apparent from the following description, reference being had to the accompanying drawing wherein a preferred embodiment of the present invention is clearly shown.

In the drawing:

Figure 1 is a schematic circuit diagram of a control circuit embodying a preferred form of the present invention; and

Figure 2 is a schematic circuit diagram illustrating a modification of the invention.

Referring to Figure 1, a transformer 10 has a core 12, a primary winding 13 and a secondary winding which is preferably divided into halves 14 and 15. One side of the primary winding 13 is connected to a power supply line lead 16

through a main line circuit control switch 17. The other side of the primary winding is connected to a power supply line lead 18 through contacts 19 and 20 and a contact bridging element 22 of a switch 23. The switch 23 is normally biased to the open circuit position by a spring or other suitable means 24 and is actuated to the closed position by a manually operable operating member or push button 25.

10 One end of the half 14 of the secondary winding is connected to ground at 26. The other end of that half of the secondary winding is connected to an electrode 27 of a gas discharge tube 28. One end of the half 15 of the secondary winding is connected to an electrode 29 of the gas discharge tube 28. The other end of the half 15 of the secondary winding is connected to ground at 30 through a solenoid or electromagnet winding 32 which preferably has low impedance. 15 The halves 14 and 15 of the secondary winding are wound and connected so that their potentials are additive and their combined voltage is applied to the gas discharge tube electrode. The ends of the halves of the secondary winding 20 which are connected to ground at 26 and 30 preferably comprise the mid-point of the winding.

25 Another object of this invention is to provide a core 33 of magnetic material is magnetically associated with the electromagnet winding 32 and is secured to the contact bridging element 22 to hold the switch 23 in the circuit closing position against the biasing force of the spring 24 after the switch is actuated to the closed position and during the flow of normal current 30 through the winding 32.

35 In the operation of the circuit shown in Figure 1, the main line control switch 17 is actuated manually or otherwise, but does not complete the circuit from the power supply line leads 16 and 18 to the primary winding 13 until the switch 23 is manually closed. The actuation of both of the switches 17 and 23 is necessary to the completion of the power supply circuit to the primary winding. When the switch 23 is actuated to the 40 closed position after the closing of the switch 17, the secondary winding potential is applied to the electrodes 27 and 29 of the gas discharge tube 28 to effect a discharge within that tube and a consequent current flow through the gas discharge 45 tube and the halves of the secondary winding. This current flow under normal operating conditions energizes the electromagnet winding 32 which is connected in series with the half 15 of the secondary winding, and thereby holds the 50 switch 23 in the circuit closing position. Upon the interruption of the current flow through the secondary winding circuit, as by the failure or breaking of the gas discharge tube 28 or the 55 breaking of a lead thereto, the electromagnet winding 32 is de-energized and the switch 23 is 60

opened by the biasing force of the spring 24. The opening of the switch 23 opens the circuit to the primary winding 13, which circuit remains open until manually reclosed.

Referring to Figure 2, parts like those referred to in the description of Figure 1, bear similar reference numerals. The power supply line lead 18 is connected to one side of the primary winding 18 through the main line control switch 17. The power supply line lead 16 is connected to the primary winding 13 through contacts 34 and 35 and a contact bridging element 36 of electromagnetically actuated switch 37. An electromagnet actuating winding 38 of the switch 37 is connected to the power supply line lead 16 through a normally closed temperature responsive switch 39 which preferably has a bimetallic element 40 connected in the circuit between the power supply line lead 16 and the actuating winding 38. The bimetallic element 40 has one end anchored at 42 and the other end free to flex to open the circuit to the actuating winding. The other end of the actuating winding 38 is connected to the power supply line lead 18 through the main line control switch 17. A resistance heating element 43 is closely associated with the bimetallic element 40 to insure heating of the element, and is connected directly to the power supply line lead 16 and to the power supply line lead 18 through the switch 17. The switch 37 has a movable magnetic core 44 connected to the contact bridging element 36 and adapted to be actuated by the actuating winding 38. This switch also has a holding winding 45 which is connected in series with, and between the halves 14 and 15 of the secondary winding.

In the operation of the circuit shown in Figure 2, the closing of the main line control switch 17 normally closes a circuit from the power supply line leads 16 and 18 to the actuating electromagnet winding 38 through the bimetallic temperature responsive switch 39. At the same time a circuit is closed from the power supply line leads 16 and 18 to the resistance heating element 43. The actuating electromagnet winding 38 effects closure of the switch 37 to close the circuit from the power supply line leads to the primary winding 13 of the transformer. The energization of the transformer secondary winding comprising the halves 14 and 15 provides operating potential for the gas discharge tube 28. Upon the commencement of the discharge within the tube 28, current flow through the secondary winding and the holding winding 45, which is connected in series therewith, energizes that holding winding to maintain the switch 37 in the closed position during the normal operation of the gas discharge tube.

The heating of the resistance heating element 43 which follows the closing of the switch 17 transfers heat to the bimetallic element 40 to effect flexure of that bimetallic element and the opening of the circuit to the actuating electromagnet winding 38 through the contacts of the switch 39. As long as the switch 17 remains closed, the resistance heating element 43 remains heated and maintains the bimetallic element 40 in a flexed position. A period of time is required for the bimetallic element to return to the circuit closing position after the opening of the switch 17. As a consequence, during normal operation, only the holding winding 45 maintains the switch 37 in the closed position, and any abnormal condition which interrupts the current flow through the gas discharge tube 28 or the secondary wind-

ing circuit results in the opening of the switch 37 by the biasing spring 41. The operation of the circuit cannot then be re-established until after the switch 17 has been opened for a period of time sufficient to allow the heating element 43 and bimetallic element 40 to cool and re-establish the engagement of the contacts of the switch 39 and until the switch 17 is again manually closed.

While the embodiment of the present invention as herein disclosed, constitutes a preferred form, it is to be understood that other forms might be adopted, all coming within the scope of the claims which follow.

What is claimed is:

15. 1. A control circuit for an illuminating system comprising, in combination, an illuminating device, a power supply line, a transformer having a primary winding adapted to be connected to the power supply line and a secondary winding divided into substantially equal halves, said halves of the secondary winding having center and outer terminals, said illuminating device being connected to the outer terminals, two switches being connected in series with the power supply line and primary winding, both of said switches being manually operable to the closed position and one of the switches being normally biased to the open position and having electromagnetic holding means for holding the switch closed, the center terminals of the secondary windings being grounded, and at least one of the ground connections to the center terminals of the secondary windings being made through said electromagnetic holding means.
- 30 2. A control circuit for high voltage illuminating systems comprising, in combination, a gas discharge illuminating device, a power supply line, a transformer having primary and secondary windings, the primary winding being connected to the power supply line through a main line control switch and an auxiliary switch, the secondary winding being divided into halves and providing potential for operating the illuminating device, said auxiliary switch including electromagnetic switch operating means and electromagnetic switch holding means for holding the switch closed, a temperature responsive switch having a heating element, said heating element being connected to the power supply line through the main line control switch, said electromagnetic switch operating means being connected to the power supply line through the main line control switch and the temperature responsive switch, and said electromagnetic switch holding means being connected in series with the halves of the secondary winding.
- 45 3. A control circuit for illuminating systems comprising, in combination, a power supply line, an illuminating device, a plurality of switches in series with the power supply line which must each be closed for providing potential for the operation of the illuminating device, one of said switches being manually operable, electromagnetic means for operating another of the switches, temperature responsive switch means for controlling the operation of the electromagnetic means, and rendering the electromagnetic means ineffective during normal operation of the illuminating device, and holding means effective during normal operation of the illuminating device for retaining the electromagnetically operated switch closed during normal operation of the illuminating device.

OSCAR A. PEARSON.
